UNITED STATES PATENT OFFICE.

NATHANIEL G. WARTH, OF COLUMBUS, OHIO.

TELEPHONE REPEATER SYSTEM.

No. 894,170.

Specification of Letters Patent.

Patented July 21, 1908.

Original application filed April 23, 1906, Serial No. 313,192. Divided and this application filed April 22, 1907.
Serial No. 369,524.

To all whom it may concern:

Be it known that I, NATHANIEL G. WARTH, a citizen of the United States, residing at Columbus, in the county of Franklin and State of Ohio, have invented a certain new and useful Improvement in Telephone Repeater Systems, of which the following is a specification.

This invention was originally disclosed in my application filed April 23, 1906, pursuant to which my Patent No. 845,282, dated February 26, 1907, was issued and is divisional with reference to said application.

The present invention relates more particularly to the repeater circuits and the repeater or relay apparatus at a repeater station, and generally stated, one object of my invention is to provide a reciprocally operative repeater apparatus operating without the use of switches for changing the circuit arrangement for the transmission in the reciprocal directions, and also consists in circuits for a double or twin system in which each of the two repeater instruments receives the weakened initial currents from its respective line or circuit, reproduces the currents with exactness and augmented volume, and retransmits them into the associated line circuit, with the full effect of the transmitter. Each of the two transmitters thus sending its whole current into the line circuit assigned it and without division of the current between the two circuits connected. Such division takes place in the system now in commercial use and results in inferior transmission.

A further object of my invention is to establish for each of the repeaters associated for reciprocal transmission, between two given circuits, or two sections of a compound circuit, a constant electrical balance in their respective local circuits, which balances are maintained regardless of the state of balance existing in the inductively associated and respective line circuits. These maintained electrical balances are created in the receiver local circuits by providing differential or neutralizing action upon each repeater-receiver to the locally set up currents. This local balance is not disturbed or upset by the inductively received initial line currents in either receiver element, yet each receiver element is rendered sensitive and responsive to such inward currents. These constant electrical balances are maintained by inductively operating the repeater-receiver element of

each repeater by means of translating devices with the line circuit sections. Thus, any unbalanced condition, whether normal or accidental, in either line circuit section, or an unbalanced state of one section with relation to the other, will not upset the local balance as established. Were it not for this balance a local or self-action, producing a "howling" or "singing" noise, would be created by the apparatus, and were the balance not maintained in an independent manner by both repeater-receiver circuits being physically separated from the line circuits, yet operatively associated therewith by inductive means, such interfering self-action would be set up whenever the balance in the line circuits is materially disturbed. All metallic telephone circuits are electrically balanced, each wire with its mate, for normal operation, and in the other repeater systems now in commercial service the line sections must also be carefully and individually balanced, as circuits, on each side of the repeater apparatus. The other systems require for such special balancing adjustable resistances and capacities in the circuits, or derived or artificial balancing circuits and artificial lines, etc., each of which methods dissipates the transmitted currents and seriously reduces the volume and efficiency of the transmission.

The figure illustrated herewith is one embodiment of my invention and will be readily understood from the following description.

The figure is a diagram representing two electrically widely separated telephone stations with their respective line circuits terminating at an intermediate point at a repeater station in a double or twin reciprocally operative telephone repeater instrumentality embracing two sets or units of apparatus. Each of said units comprises an independent repeater electro-magnetic receiver in a closed local circuit and having a magnetically controlled armature or diaphragm operatively connected with a variable resistance transmitter all being associated in repeater relation, and the two repeater units being electrically associated in reciprocally transmitting repeater relation. Both units, together with their local circuits, local batteries and their local windings of the line translating devices or induction coils are inductively associated with their respective line circuits through the medium of their respective secondary windings of the induction

coils connected therein. Herein the terms "primary" or "local" and "secondary" with reference to the "windings" of the line induction coils are not material, as each 5 winding is alternately used as a primary or as a secondary, according to the trend or direction of the transmission.

The drawing herewith illustrates a twin or double repeater arrangement comprising two 10 sets of apparatus, R and R^2 , with neutralizing windings, N and N^2 , respectively incorporated on each receiver core but connected in the local circuit of the opposite receiver. The two principal windings N^3 and N^4 of 15 these receivers are so disposed as to actuate each receiver-transmitter by currents from either line induction coil C or C^2 when the latter are caused to transform currents from the line circuits L and L^2 , and these said neutralizing windings, together with windings N and N^2 , also operate to neutralize or prevent 20 magnetic action in the receivers from currents flowing through them from the transmitter local batteries B and B^X . In this apparatus the receiver coils are shown included 25 in the primary or transmitter local circuits for the purpose of reducing the apparatus, circuits and line induction coil windings to a minimum, and avoiding current losses in unnecessary windings and conversions. The 30 re-transmission is effected in both directions, as both repeaters act in unison, but the transmission is in but one direction from each instrument. Full transmitting efficiency is 35 thus secured in one direction from each transmitter. There is a practical separation of the two sections of the compound circuit from direct induction or transmission effects into each other, as the low converting 40 efficiency of the low wound receivers is practically negligible for such transmission. This arrangement affords no opportunity for interfering local action in the repeaters to cause "howling" as the receiver coils are 45 differentially connected and neutral to the primary effects, and the line conditions if unbalanced cannot affect the receiver circuits to unbalance them, as the line induction coils C and C^2 conductively separate the receiver 50 circuits proper from the line circuits so that transforming currents only can affect the repeaters. The broken arrows in this view conventionally indicate a transforming line current set up at the terminal telephone 55 S² and the solid arrows indicate the local currents primarily caused to flow by the action upon the cores of the receivers by the transformed or induced line current. A reversal of transmission produces like effects in the 60 opposite direction without switches for changing the circuit arrangement, as in some repeater systems.

To adapt the circuit to composite or through signaling service the two sections L 65 and L^2 of the compound circuit are connected

together around the repeater apparatus by the conductors A and A^2 in which suitable reactance or choke coils F and F^2 are included. The condensers J, J^2 , etc., are required when the composite or signaling service is separately operated on the two wires of the metallic circuit in a well-known way. Other composite or signaling apparatus and circuit conditions are not illustrated or explained as they are well-known and this invention does not particularly contemplate that class of service.

The operation is further described and the circuits traced as follows: A primary current set up at the terminal station telephone S² produces an initial inducing line current in line circuit section L² in the direction indicated by the broken arrow near the induction coil C²; a corresponding induced current is set up in the associated local or primary circuit, which is connected with the then secondary winding of coil C². The current flows from the coil through the windings N^4 and N of the repeaters, (see broken arrows next local circuit) thence joining flows 90 through transmitter M of repeater R, which latter is more particularly associated with line circuit section L. The consequent actuation of transmitter M², which is actuated by winding N⁴, sets up from local battery B a 95 repeating current which is a duplicate of that set up in the first mentioned associated local circuit by transmitter M and battery B^X. These duplicate primary currents are balanced in both receivers through the neutralizing windings N and N^2 acting differentially to windings N^3 and N^4 respectively on the receivers and operate to neutralize the receivers and create an inert state thereof and of the transmitters to the locally produced 100 currents, thus preventing local action of the apparatus and avoiding the noise termed "singing" or "howling". It will be observed that these double or twin local circuits have only an inductive operative relation to 105 the line circuit sections, thereby insuring the continuance of the balances set forth regardless of variations of balances in the line circuits. The duplicate current (see the solid arrows) set up in the local circuit by 110 battery B flows through the then primary winding of repeating coil C, thence through principal winding N^3 and neutralizing winding N^2 of the repeater-receivers, thence 115 through transmitter M² of repeater R², which latter is more particularly associated with line circuit section L², thence returning to the battery. Similar actions and effects are simultaneously set up in the first mentioned local circuit by transmitter M and battery B^X by the action of principal winding N^4 and neutralizing winding N. Hence 120 both receivers are rendered neutral and inert to the locally set up and reproduced currents. The currents thus set up by 125

transmitter M^2 are induced into line circuit section L by the induction coil C and are transmitted thence to the terminal station telephone S, thereby completing the cycle of initial transmission, repetition, and retransmission. It will be understood that the reciprocal of these current-flows and effects occurs with each change in the direction of transmission or use of the line.

For the establishment of an initial magnetic field in the receivers of the repeaters R and R^2 for their sensitization I prefer to employ for each a permanent magnet.

The system may be operated in connection with superposed circuits and their currents, and also with a flexible cord-circuit and other desired auxiliary apparatus.

Modifications of this invention as illustrated herein may be made without departing from the substance of it.

What I claim and desire to secure by Letters Patent is:

1. In a relay for telephone-lines, two induction-coils, two transmitting devices, magnetically-controlled means operatively connected therewith, and two independent electro-magnetic means included in closed local circuits solely with the secondaries of said induction-coils.

2. In a reciprocal telephone repeating system, the combination with telephone-line sections, of repeating-relays, each inductively responsive to currents originated in its respective line-section and unresponsive to currents produced by it in the other line-section, as set forth.

3. In a telephone repeater system, the combination with a main line circuit, of two sets of receiver transmitter-repeaters in local circuits associated with said main line inductively, and means for balancing said receivers in the local circuits against local self-action and reproduced line currents.

4. In a telephone repeater apparatus, local circuits, two repeaters in inductive local relation to a line, local balances for the repeaters producing a differential flow of local currents for controlling the repeaters to render them inoperative or inert to said locally produced currents.

5. In an automatic reciprocal telephone repeating system, the combination of a main telephone circuit divided into independent sections, two repeaters, differential windings in balanced relation to the reproduced or locally set up currents, circuit means for rendering the repeaters responsive to the originating line currents, local circuits for the repeaters inductively associated with the main circuit, current supply for the repeaters for renewing the originating line currents with increased power, each repeater transmitter operating to induce its reproduced current in one line section.

6. In a double or twin telephone repeater

apparatus, twin local circuits each embracing a current supply and a receiver and transmitter associated in repeater relation to each other, means for associating both receivers and both transmitters with a line inductively, electrical balances in the twin local circuits for each repeater for preventing local self-action therein, the said inductive associating means rendering the said balances self-dependent and constant.

7. In a double telephone repeater, two primary or local circuits each embracing in combination a primary or local winding of an induction coil, a source of current supply, and a receiver and transmitter associated in repeater relation.

8. In a telephone repeater, the combination of two receivers having neutralizing differential windings and two transmitters mechanically and electrically associated with said receivers in repeater relation, two local circuits each including a winding of each receiver for balancing it against local self action, a transmitter, a current supply and means for associating both repeaters with a line inductively, whereby the said balance against local action is made constant.

9. In a telephone repeater system, the combination of two line circuits having telephones, two local or primary circuits, one for each line circuit, repeating or induction coils inductively uniting said line circuits to their respective local circuits, two independent or separate telephone repeaters connected in said local circuits, each repeater being particularly associated with its respective line circuit so that its transmitter operates through its particular local circuit and coil to induce its entire retransmitting current into that line circuit, current supply for the repeater-transmitters, associated divided windings for the repeater-receivers and a circuit arrangement and electrical balances whereby local or self action in the repeaters is prevented.

10. In a telephone repeater system, the combination of two line circuits having telephones, two local or primary circuits one for each line circuit, repeating or induction coils inductively uniting said line circuits to their respective local circuits, two independent or separate telephone repeaters connected in said local circuits, each repeater being particularly associated with its respective line circuit so that its transmitter operates through its particular local circuit and coil to induce its retransmitting current into that line circuit, each repeater being inductively responsive to currents originated in its respective line circuit and unresponsive to currents produced by it in the other line circuit, current supply for the repeater-transmitters, divided windings for the repeater receivers and an associated circuit means whereby electrical balances are maintained and local or self action in the repeaters is prevented.

11. In a telephonic repeater system, the combination of induction coils, two telephone lines or line sections, a repeater apparatus joining said lines or line sections, said repeater apparatus consisting of twin units within twin local circuits and operating simultaneously, each receiver having two windings, one of which is in circuit with its twin receiver, each receiver actuating its transmitter which is connected in the other side or opposite of the twin circuits, to transmit in that one direction, the twin local circuits working inductively with the line, the incoming or received currents energizing the receivers and actuating the transmitters, the retransmitting currents being made to flow differentially through the receiver windings and thereby prevent local action upon the transmitters.
12. In a reciprocal telephone repeater system, a repeating apparatus at an intermediate station on a line circuit connected through said repeating apparatus for repeater service, said apparatus embracing two independent units, each unit comprising a receiver and a transmitter associated in repeater relation, the units being electrically associated in repeater relation and being in inductive relation to the line circuit, and associated local circuit means whereby the repeaters are constantly maintained unresponsive to their reproduced and locally set-up currents but are responsive to the initial line currents.
13. In a telephone repeater system, the combination of two main telephone circuits or two sections of a circuit, two repeater units, two induction coils, one for each main circuit, associated local repeater circuits each inductively connected with its respective main circuit or circuit section, each repeater receiver and one repeater-transmitter associated with each local circuit including a current supply, means for rendering the repeaters insensitive to the locally set up and retransmitted currents, each of said induction coils constituting a common medium for receiving from and sending to their respective main circuits the inward and the reinforced outward currents.
14. In a telephone repeating system, the combination of two main line circuits extending from outlying telephone stations and joined at a repeating station by a double telephone repeater, local repeating circuits for the repeaters, induction coils uniting said local circuits to their main line circuits respectively, the receiver magnets each having two windings, one winding being in each of the local repeating circuits together with the battery and the transmitter for that circuit, the battery currents energizing the receiver windings differentially to produce inaction to the local currents and the induced line circuit currents operating the receivers and actuating their transmitters, the re-transmitting currents set up being induced into the line circuits through the induction coil windings uniting the local repeating circuits to their respective main line line circuits.
15. In a reciprocal telephone repeater system, a main line circuit, two co-operating telephone repeaters at a repeater station on said line, local circuits for the repeaters and a source of current supply therein, said local circuits being inductively associated with the line circuit, differential windings in said local circuits for balancing the current effects for the repeaters to render the same unresponsive to their reproduced currents yet sensitive to the initial line currents.
16. In a telephone repeater apparatus, the combination of two repeaters each comprising a receiver and transmitter associated in repeater relation, local circuits for the repeaters, each receiver being connected up in one of said local circuits and having a balance, said balance including differential windings for preventing interfering operation by its locally set up or reproduced currents.
17. In a telephone repeater, the combination of two receivers and two transmitters associated together in repeater relation, local circuits therefor, a current supply for the transmitters, each receiver having differential windings in the local circuits in electrically balanced arrangement, and also having its transmitter connected to transmit in but one direction.
18. In a telephone repeater system, two repeaters, a sectionally divided line circuit, local circuits, inductive windings associating the line and local circuits, local current supply, two differential windings in the local circuits controlling the receiver elements to render the same inert to the reproduced currents but active to the initially received line currents, the transmitter elements being arranged to transmit into but one line section.
19. In a telephone repeater system, the combination of a main circuit formed of two circuits or two circuit sections associated for repeater service, two repeaters, each comprising receiving and transmitting mediums, induction coil windings operatively associating all said repeater mediums inductively with said main circuit, each receiver actuating its repeater transmitter and each transmitter repeating into a different circuit section, each receiver being rendered inert by differential windings to the local or reproduced currents flowing in the differential windings but sensitive to the initial inward currents flowing through said windings non-differentially.
20. In a telephone repeater apparatus, the combination of two repeaters, local circuits therefor, said local circuits being divided and containing induction coil windings in inductive relation to a line circuit and connected up or arranged to cause locally produced

currents in the repeater apparatus to flow differentially with relation to the receivers to provide a neutral state for each and to avoid reaction.

5 21. In a telephone repeater system, the combination of a sectionally divided main line circuit, induction coil windings, with the secondary division thereof included in the line circuit sections, divided local circuits including the primary or local division of the induction coil windings; local battery or current supply for retransmitting, two repeating telephones, and differential windings therefor included in the local circuits and being in inductive relation to the line circuit, the receivers of the repeater being controlled by individually established electrical balances in the local circuits, each balance including a differential winding and the arrangement adapted to produce neutral effects by the locally set up currents upon the receivers, each receiver being actuated by initial line currents from one line section to individually actuate its respective transmitter to vary its

battery current and transmit renewed or repeated duplicate currents into the associated or opposite line section only, whereby reciprocal re-transmission is obtainable and without reactive interfering local self-action in the apparatus or reaction by the reproduced currents, and wherein the local balances are constantly maintained regardless of absence of balance in the main line circuit. 25

22. In a telephone repeater, two repeaters, two divided local circuits by which the repeaters are controlled, each repeater having a local differential current balance to prevent interfering reaction. 30

23. In a telephone repeater apparatus, two repeaters reciprocally co-operative, two divided local circuits, one for each repeater, in which the repeaters are controlled by means of differential local current balances to prevent interfering reaction. 40
